THE NORRIS PETERS CO., PHOTO-LITHO., WASHINGTON, D. C.

UNITED STATES PATENT OFFICE.

FERDINAND MATHEYER, OF NEW YORK, N. Y.

INTESTINE-CLEANER.

SPECIFICATION forming part of Letters Patent No. 722,525, dated March 10, 1903.

Application filed July 30, 1902. Serial No. 117,641. (No model.)

To all whom it may concern:

Be it known that I, FERDINAND MATHEYER, a citizen of the United States, and a resident of the city of New York, borough of Manhattan, in the county and State of New York, have invented a new and Improved Intestine-Cleaner, of which the following is a full, clear, and exact description.

The invention relates to butchering; and its object is to provide a new and improved intestine-cleaner which is simple and durable in construction, very effective in operation, and arranged to thoroughly and quickly wash and lengthwise split open the intestines without requiring great skill on the part of the operator.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a side elevation of the improvement. Fig. 2 is a rear side elevation of the same, showing the cover of the hood for the gearing in an open position. Fig. 3 is a plan view of the improvement. Fig. 4 is a cross-section of the same on the line 4 4 of Fig. 3. Fig. 5 is a similar view of the same on the line 5 5 of Fig. 3; and Fig. 6 is a sectional plan view of the nozzle-guide, the section being on the line 6 6 of Fig. 1.

On the front end of the bed A, on which the machine is mounted, is bolted or otherwise secured a longitudinally-extending nozzle-guide B, having a passage B', connected at the rear end with a similar passage A', formed in the bed A and connected with a water-supply pipe C, as plainly shown in Fig. 6. The forward end of the guide B and its passage B' terminate in a knob-like nozzle B'', adapted to pass into the intestine, so that the water from the nozzle washes the intestine as the latter is fed forward over the guide B by a pair of toothed feed-disks D and D', secured on a transversely-extending shaft D'', journaled in suitable bearings on the free end of a swing-frame E, provided at its rear end

with trunnions E', mounted to turn in bearings A'', forming part of the bed A. The extreme rear end of the swing-frame E is provided with a counterbalancing-weight E'' 55 to permit the operator to conveniently swing the frame E upward at its forward end for the purpose hereinafter more fully described.

The top B''' of the nozzle B, below the peripheral faces of the feed-disks D D', is segmental and in close proximity to the teeth of the disks, and the said teeth extend close to the outer faces of longitudinally-extending ribs B'', forming part of the nozzle-guide B, so that when the machine is in operation the 65 said teeth of the feed-disks engage the intestine at two points to feed the same lengthwise forward over the nozzle-guide B and to a slitting-disk F, extending between the rear bottom portions of the disks D and D' and into 70 a longitudinally-extending slot B'', formed in the nozzle-guide B.

The slitting-disk F is secured on a shaft F', journaled in the forward end of the swing-frame E, and the said feed-disks D and D' 75 and the slitting-disk F are rotated in unison from the main shaft G, journaled in the trunnions E' of the swing-frame and carrying fast and loose pulleys G' and G'', connected by a belt with other machinery for imparting a ro- 80 tary motion to the shaft G. The pulley-belt referred to is shifted from one pulley to the other by a shifting-fork G'', held on a shaft G'', journaled in suitable bearings carried by the swing-frame E, and the forward end of 85 the shaft G'' is provided with a handle G''' under the control of the operator standing in front of the machine and guiding the intestines to the nozzle B'' of the guide B.

The gearing for driving the disks D, D', and 90 F from the main shaft G is positive and consists of a sprocket-wheel H, secured on the shaft G and connected by a sprocket-chain H' with sprocket-wheels H'' and H'', of which the sprocket-wheel H'' is attached to the shaft 95 D'' and the sprocket-wheel H'' is secured on the shaft F'. The sprocket-chain H' also passes over a tightening sprocket-wheel H'', journaled on an arm H'', fulcrumed on the shaft F' and secured in place by a clamping- 100 bolt H'', held on the swing-frame and engaging a segmental slot H''' in the arm H'', as

plainly indicated in Fig. 2. Now when the shaft G is rotated then the sprocket-wheel H by the sprocket-chain H' and sprocket-wheels H² and H³ imparts a rotary motion to the shafts D² and F' to rotate the feed-disks D and D' and the slitting-disk F in unison and in the direction of the arrows a' and b'.

In order to prevent lost motion in the gearing, it is only necessary to adjust the arm H⁵ so that the tightening sprocket-wheel H⁴ takes up lost motion and insures easy and noiseless running of the machine.

The driving-gear described is inclosed in a hood I, having a hinged cover I', so as to render the gearing dust, dirt, and water proof. The hood I is attached to the swing-frame E, which also carries a hood J, having a hinged cover J', partly inclosing the disks D, D', and F.

When the machine is running, the operator passes one end of the intestine over the nozzle B² until the teeth of the feed-disks D D' take hold of the intestine and feed the same along the nozzle-guide B. The teeth of the feed-disks D D' in engaging the intestine stretch the same over the ribs B⁴, and as the peripheral cutting edge of the slitting-disk F extends between the said ribs B⁴ it is evident that the cutting edge effectively cuts the intestine open at the top.

When it is desired to render the disks D, D', and F inactive without stopping the said disks, then the operator swings the swing-frame E upward and locks the same in an uppermost position by a pin or like device inserted in an aperture K' in a segmental arm K, projecting upwardly from the bed A and passing through a bearing E³, formed on the swing-frame E. (See full and dotted lines in Fig. 1.) When the swing-frame is in this uppermost position, the operator has convenient access to the nozzle-guide B for cleaning or repairing purposes and access to the disk for sharpening the same without stopping the machine. When the frame is in the uppermost position, the rotation of the main shaft G, the gearing, and the disks D, D', and F may be stopped, and then the operator has convenient access to the said disks for repairing or other purposes.

It is understood that when the frame E is

in its lowermost position its front end rests on the front end of the bed A, so as to hold the disks D, D', and F in proper relation to the nozzle-guide B.

Having thus described my invention, I claim as new and desire to secure by Letters Patent—

1. An intestine-cleaner comprising a pair of revoluble toothed feed-disks, a revoluble slitting-disk extending between the feed-disks, a fixed guide for the passage of the intestine, having a slot for the slitting-disk, longitudinal ribs on the walls of the slot and projecting above the upper face of the guide, and a nozzle connected with the water-supply and adapted to pass into the intestine in advance of the said disk, a main shaft, a gearing for rotating the said disk from the said main shaft, and a swing-frame fulcrumed on the main shaft and carrying the disks and the gearing, as set forth.

2. An intestine-cleaner provided with a fixed guide having a longitudinal slot, a water-passage terminating in a nozzle at the free end of the guide, and longitudinal guide-ribs projecting from the top of the guide, on opposite sides of the slot, as set forth.

3. An intestine-cleaner comprising a pair of revoluble toothed feed-disks, a revoluble slitting-disk extending between the feed-disks, a fixed guide for the passage of the intestine, having a slot for the slitting-disk, a nozzle connected with a water-supply and adapted to pass into the intestine in advance of the said disk, a main shaft, a gearing for rotating the said disk from the said main shaft, a swing-frame fulcrumed on the main shaft and carrying the disks and the gearing, a hood for the gearing, and a hood for the disks, both hoods forming parts of the swing-frame and provided with hinged covers, as set forth.

In testimony whereof I have signed my name to this specification in the presence of two subscribing witnesses.

FERDINAND MATHEYER.
